UNITED STATES PATENT OFFICE

LEO L. BECK, OF LINDEN, NEW JERSEY, ASSIGNOR TO CLAUDE NEON LIGHTS, INC., OF NEW YORK, N. Y., A CORPORATION OF NEW YORK

NONHARDENING VACUUM TUBE LAMP

Application filed June 2, 1926. Serial No. 113,147.

This invention relates to vacuum tube lights, and more particularly to lights in which a column of gas under low pressure, such as neon, is caused to glow by the passage of an electric current therethrough.

Lights of this type, as is well known, have a life that is limited, as at present constructed. After they have been in operation for a certain length of time, the voltage required to operate them increases to such an extent that the light is for all practical purposes inoperative. This process is termed in the art "hardening" and is known to be due to a lowering of the pressure of the gas within the tube.

While it might be supposed that this "hardening" is due to leakage of gas from the tube, it has been found that this is not the case. At least, the phenomenon is mainly due to causes other than leakage of gas from the tube.

It is an object of the invention to provide a method and apparatus for preventing, or at least materially delaying the "hardening" of vacuum tube lights such as neon lamps.

It is a further object of my invention to provide a vacuum tube light having an operating life greatly in excess of the operating life of known tubes of the class described.

It is a further object of this invention to provide a vacuum tube light having means introduced therein to prevent or materially delay the "hardening" of such lights in operation.

Still other objects of my invention will be apparent from the specification.

The features of novelty which I believe to be characteristic of my invention are set forth with particularity in the appended claims.

My invention itself, however, both as to its underlying principles and as to its practical application, will best be understood by reference to the specification and accompanying drawings, in which Figure 1 represents a vacuum tube light in accordance with my invention; and Figures 2, 3, 4, 5 and 6 represent a method of introducing unheated glass chips which I prefer to use in practising my invention.

It has been found that this lowering of the

gas pressure or "hardening", is not due to leakage of gas from the tube but is due to a totally different cause. It is generally believed that when a voltage is impressed between the electrodes of a vacuum tube light, such as a neon lamp of the type shown, electrons pass into the gas and travel toward the other electrode. During their passage, they cause the neon to glow and radiate its characteristic light. Some of these electrons, however, in passing from the electrodes to the gas, appear to carry off tiny particles of metal from the electrode, which particles are "plated out" or deposited on the walls of the tube.

It has been found that these metal particles, of perhaps atomic order of size, in their passage through the gaseous space of the tube, pick up or entrap molecules or particles of neon, and carry these gas particles with them. When the metal particles are "plated out" on the wall of the tube, the neon which they have entrapped no longer plays any part in the operation of the tube and eventually so much neon is entrapped and effectively removed that the gas pressure falls below that desired and the voltage required to cause illumination increases greatly. When this takes place, the practical operating life of the tube is at an end.

It is known that when an electric current is passed through a mixture of gases from metallic electrodes, the metal particles passing through the gaseous space entrap and carry off first the lightest gas of the mixture, and leave the heavier gases until the lighter are removed. For example, if hydrogen is admitted to a neon light, even in quantities small enough so that the operating characteristics of the tube are otherwise not affected, the metal particles will entrap and carry off the hydrogen as long as it is present, and the neon will be left.

I have found that this effect may be utilized to increase the length of useful operating life of vacuum tube lights such as neon lamps, by arranging or providing for a slow evolution or introduction of hydrogen, or other substance having a similar effect, in the tube. The result of this is that there will always

be hydrogen present in the tube and so long as it is present the neon or other active constituents will not be removed. During operation of the tube the hydrogen will be plated out, and by controlling the rate of evolution or introduction of the hydrogen in the tube in such a way that it is produced approximately as fast as it is removed, a balanced operating condition is achieved which 10 results in a tube having an operating life greatly in excess of ordinary tubes.

The slow introduction or evolution of hydrogen necessary may be provided for in several ways, but I prefer to obtain it by introducing into the lamp envelope after exhaustion, some ordinary unheated glass, preferably in the form of chips, which may be distributed along the path of discharge between the electrodes of the lamp.

20 Referring now to the figure, 1 designates a tubular envelope of transparent material such as glass, having electrodes 2 disposed within the tubes, and supported on strings of glass beads 3 strung on wire, and connected to 25 lead-in wires 4 passing through a press 5. The space in the tube 1 is occupied by gas such as neon at relatively low pressure.

Unheated ordinary glass chips 6 are introduced into the tube in any suitable way, but 30 preferably in the way described and claimed in the copending application of Robert Smalley, entitled "Method and apparatus for introducing foreign substances into vacuum tube lamps, etc." filed April 30, 1926, assigned 35 to Claude Neon Lights, Inc. By unheated glass chips, I mean small particles or chips which are substantially unheated during the exhausting process.

Referring now to Figure 2, 11 designates 40 a section of tubing preferably of glass having a second portion 12 sealed thereon to form a T. The lower end of the stem of the T is closed off as at 13 and the substance to be transferred to the interior of the lamp such 45 as the unheated glass chips, is placed therein as indicated at 14. If desired, a neck portion 15 may be formed on the T on each side of the stem thereof, or at one side only if desired for convenience in sealing off and 50 moving portions of the tube.

Referring now to Figure 3 I have shown 55 diagrammatically a lamp envelope 1 in which it is desired to insert unheated glass chips 6. The T tube 11 will be sealed to the lamp envelope 1 as at 22 in such a manner as to establish contact between the interior of the T tube and the interior of the lamp envelope. The junction 22 between the T tube 11 and the lamp envelope 1 should be made air tight 60 for a purpose which will be explained later. The opposite open end of the T tube 11 may and preferably will be connected to tube 23 leading off to suitable pumps or other evacuating apparatus, not shown so that the lamp 65 may be evacuated through tube 11, thereby

avoiding the necessity of making another connection to evacuate the lamp envelope. Either before or after the T tube 11 is sealed to the lamp envelope, the material which it is desired to transfer to the interior of the lamp envelope, such as the unheated glass 7 chips 6, will be placed in the stem of the T as shown at 14. The pumps may now be started and the interior of the lamp envelope 1 evacuated. It is to be understood of course, that any necessary heating of the lamp envelope 8 may take place at this time either with or without the passage of current through the lamp and either with or without supplemental heating of the electrodes to drive off 9 occluded gases.

Since the material to be introduced is in the pocket 14 out of the path of current flow in the gas, the passage of current will not materially heat the substance to be introduced into the lamp and thereby drive off the water vapor which it contains, this of course must be avoided.

After the tube has been properly evacuated, the evacuating apparatus may be disconnected, and the proper amount of desired gas, such for example as neon, introduced by opening a valve (not shown) in the evacuating line.

It is now evident that the tube has been 95 evacuated and that it has been supplied with the proper amount of gas for operation. It should now be sealed off which may be done, for example by bringing a flame from a burner 25 to play upon the tube 11 between the junction of the T and the connection to the exhaust line.

The tube may now be aged and tested to 100 make sure that it has the proper operating characteristics, before the introduction of the foreign substance. After the tube has been 105 tested and found in good order the lamp envelope with the T tube attached thereto may be manipulated in a suitable manner to cause the foreign substance such as the glass chips 110 to flow down the stem of the T and down the top thereof as shown in Figure 5, into the envelope 1 of the lamp proper. The simplest way of producing this result is simply to invert and tilt the lamp after which the T tube may be tapped gently to dislodge the 115 glass chips.

The substance has now been introduced and the lamp will now have the desired operating characteristics. However, the T tube, or 120 what remains of it protrudes from the envelope and might be accidentally fractured thereby ruining the lamp. Therefore I prefer to seal off and remove what is left of the T tube as shown in Figure 6 by bringing the 125 burner 25 to the junction point 22 of the T tube and the lamp and sealing off and removing the T tube as will be readily understood.

While I do not wish to be bound by any 130 explanation of the effect of the unheated

glass chips, I believe that a slow and long continued evolution of water vapor takes place from the chips in the path of the discharge between the electrodes, and that this 5 water vapor disassociates into hydrogen and oxygen. The hydrogen thus liberated is entrapped and removed by the metal particles, leaving the neon in its gaseous free state, and the rate of evolution of hydrogen is such 10 that it is produced at about the same rate as it is removed. The quantity produced is dependent upon the quantity of glass chips introduced. Of course, it is to be understood that the chips must not be subjected to heating 15 during the exhausting of the tube since that would remove the water vapor which they carry, nor is it necessary to wet them, as they carry sufficient water for the purpose even when they would ordinarily be 20 considered dry.

I have found that unheated platinum produces the same effect, but is not so desirable because of its cost and because, being a conductor, it tends to short-circuit the discharge 25 through the gas.

While I have described my invention and given what I believe to be the proper explanation for the actions which take place in the tube, I wish it distinctly understood that 30 I am not limited thereby. I do know that the introduction of suitable foreign substances, such as unheated glass, unheated platinum, etc., has a marked effect in increasing the life of a vacuum tube light, 35 such as a neon lamp, whatever the theoretical explanation may be, and I do not wish to be limited to any theory of action.

While I have shown and described certain preferred forms of my invention, it is clear 40 that modifications and changes may be made without departing from the spirit and scope of my invention, as will be evident to those skilled in the art.

What I claim is:

45 1. A method of increasing the lift of neon positive column tube lamps comprising a column of gas containing neon, energized by an electric current, which comprises sealing in contact with the gas in the lamp envelope a 50 foreign substance which will maintain a slow evolution of water vapor into the interior space of said lamp.

2. A method of increasing the lift of neon positive column tube lamps comprising a column of gas containing neon, energized by an electric current, which comprises sealing in contact with the gas in the lamp envelope a 55 quantity of glass carrying water therewith.

3. A method of increasing the life of neon positive column tube lamps comprising a column of gas containing neon, energized by an electric current, which comprises sealing in contact with the gas in the lamp envelope a 60 quantity of unheated glass.

65 4. A method of increasing the life of posi-

tive column tube lamps comprising a column of gas at relatively low pressure energized by electric current which comprises maintaining within the lamp envelope a relatively slow evolution of water vapor.

5. A method of increasing the life of positive column tube lamps comprising a column of gas comprising neon at relatively low pressure energized by electric current which comprises maintaining within the lamp envelope a relatively slow evolution of water vapor.

6. A positive column tube lamp comprising a column of gas at relatively low pressure, adapted to be energized by an electric current and containing within the lamp envelope a substance capable of maintaining a slow evolution of water vapor within the envelope.

7. A vacuum tube lamp comprising a column of gas at relatively low pressure, adapted to be energized by an electric current and containing within the lamp envelope a quantity of unheated glass capable of liberating water vapor at a relatively slow rate in said envelope.

8. A positive column tube lamp comprising a column of gas comprising neon at relatively low pressure, adapted to be energized by an electric current and containing within the lamp envelope in the path of discharge a quantity of unheated glass.

In testimony whereof, I have hereunto set my hand this 21 day of May 1926
